UNITED STATES PATENT OFFICE.

CLARENCE T. McDONALD AND HERBERT R. COOK, OF CHICAGO, ILLINOIS, ASSIGNEES
TO CHICAGO JEFFERSON FUSE & ELECTRIC COMPANY, OF CHICAGO, ILLINOIS, A
CORPORATION OF ILLINOIS.

CARTRIDGE FUSE.

Application filed February 9, 1925. Serial No. 7,759.

This invention relates to cartridge fuses of the so-called knife blade type, and one of the objects of the invention is to produce a fuse of this type in which a majority of the individual elements which it is necessary to remove from the casing in the operation of refilling the fuse are secured together as a unit, so that the number of separate pieces to be handled while refilling the fuse is reduced to a minimum. To this end the invention contemplates securing together in a single group or unit the two terminal blades, an insulating bridge section connecting said blades, a fusible element, and a washer which forms a closure for one end of the casing.

Another object which is supplemental to the foregoing object is to provide a novel means for connecting the insulating bar of the so-called bridge section to the terminal blades, and to provide a novel relation between the terminal blades, the bridge section, and the fusible element and its attaching means.

A further object of the invention is to provide novel means for closing the casing and for securing the terminal blade unit in place therein in such a manner that the said unit may be quickly removed from the casing and replaced and secured therein when refilling the fuse. In carrying out this object we have provided a novel construction and relationship of washer, blade and head by which the blade is held in fixed position in the casing.

Further objects and advantages of the invention will be understood from the following detailed description, taken in connection with the accompanying drawings, in which

Fig. 1 is a longitudinal central sectional view through one form of fuse embodying the features of our invention, the terminal blade unit being shown in elevation.

Fig. 2 is a longitudinal section taken in a plane at right angles to Fig. 1.

Fig. 3 is a sectional detail view showing one of the closing washers.

Fig. 4 is an end elevation of the casing head which cooperates with the washer seen in Fig. 3.

Figs. 5 and 6 are opposite side views of the closing washer at the other end of the casing.

Fig. 7 is an end elevation of the head of the casing which cooperates with the washer seen in Fig. 5.

Fig. 8 is an elevation of one form of terminal blade unit removed from the casing.

Fig. 9 is a perspective view of one of the clips of the bridge section.

Figs. 10 and 11 are views similar to Fig. 8 but showing modified forms of terminal blade units carrying two and four fusible elements respectively.

Figs. 12 and 13 are perspective views of the end clips of the bridge sections used in the forms shown in Figs. 10 and 11 respectively.

Fig. 14 is a section taken in the plane of line 14—14 of Fig. 8.

Fig. 15 is a detail view of a fusible element.

While we have shown in the drawings and will herein describe in detail the preferred embodiments of our invention, we desire to have it understood that this disclosure is given for the purpose of representing some of the specific ways of carrying out our invention and is not intended as a limitation thereof to the constructions disclosed. We aim to cover in the appended claims all modifications and alternative constructions falling within the scope of the invention as limited by the state of the prior art.

In the preferred embodiment of the invention herein shown the fuse comprises a tubular casing composed in the present instance of an insulating tube 20 having two metallic heads 21, 22, attached to opposite ends thereof in any suitable way. The head 21 has at one end a plurality of abutments or webs 23, in this instance four, extending radially inward, the adjacent pairs of said webs forming between them pockets or recesses 24 which receive bosses 25 formed on the inner face of a disk 26 which constitutes a closure for the end of the casing. This disk has a diametrical slot through which one of the terminal blades extends. The cooperating recesses and bosses 24, 25 prevent relative rotation of the head 21 on the one hand and the disk 26 and its terminal blade on the other, for a purpose to be presently explained. A clamping member, 100 which in this instance is in the form of an annular cap 27, surrounds the terminal blade and has threaded engagement with the head 21 to secure the disk 26 in place.

The other head 22 has a web or end wall 105 28 which closes approximately one-half of the end of the casing, and in the inner edge of this end wall is formed a recess 29 shaped to

receive a part on the adjacent terminal blade, the portions 28^a of said wall 28 at opposite ends of the recess 29 constituting abutments to cooperate with shoulders on the terminal blade as will be seen later. A disk 30 closes this end of the casing and has a diametrical slot through which the terminal blade extends. The disk is shaped to conform to and cooperate with the head 22 and the terminal blade to secure the blade in place in the head. For this purpose the disk 20 has a laterally offset portion 31 which is defined by an arcuate edge 31^a and a chord-like edge 31^b, the latter being irregularly shaped to conform to the same part on the terminal blade which seats in the recess 29 in the end wall of the head 22.

The terminal blade unit as a whole, in the preferred forms herein shown, comprises two blades 32 each carrying a ledge or continuous shoulder 33; one or more fusible elements 34 connecting said blades; a bridge section composed of two metallic clips 36 embracing said blades and joined by an insulating bar 37; and the disk 26 carried by and fixed to one of said blades. The inner portions of the blades are narrower than the outer portions forming shoulders 38 which abut against the outer faces of the webs 23 and 28 of the heads 21, 22. The ledges 33 are, in this instance, composed of small oblong plates having rounded ends and having central slots which may be slipped over the narrower portions of the blades. Said ledges lie closely along the shoulders 38 on the blades and are secured rigidly to the blades in any suitable way as, for example, by upsetting the adjacent edge portions of the blades as seen at 39. These ledges are shorter in length than the width of the wider portions of the blades to leave portions of the shoulders 38 on the blade exposed, but the ledges are wider than the thickness of the blades for a purpose to be later explained.

The disk 26 is preferably fixed permanently to its blades although such permanent relation is not essential. In the present instance the disk abuts against the adjacent ledge 33 and is so locked by upsetting the edges of the blade along the outer face of the disk as indicated at 26^a.

Each of the clips 36 of the bridge section comprises two perpendicular portions, one of which has an aperture or slot 47 to be slipped over the narrower portion of the blade and the other of which extends parallel to the blade and is attached to the insulating spacer bar 37 of the bridge. The fusible element or elements are secured to the blades in the present instance by bolts 40 passing through apertures in the element and the blades and having nuts 41 whereby the element may be tightly clamped. In the particular construction shown in Figs. 1, 2 and 8 wherein a single fusible element is

used, the bolt passes first through a washer 42, then through the apertures in the fusible element and the blade and then through an aperture in a portion of the clip of the bridge section, said clip portion in this form extending directly alongside the face of the blade and being clamped thereto by the bolt and the nut. Said clip portion is offset at 43 immediately adjacent to the periphery of the nut and thereby holds the nut from turning so that the bolt and nut may be tightened by a single tool applied to the bolt head.

In the form of bridge unit seen in Fig. 10 wherein two fusible elements 34 are used, the said elements are preferably located at opposite sides of the blade ends and are embraced by a pair of washers 42 against which the heads of the bolts 40 and the nuts 41 bind.

In this arrangement it is desirable that the bridge section be spaced farther away from the plane of the blades and therefore the portions of the clips 36 which extend parallel to the blades are spaced from the blades. In these clip portions we preferably provide apertures 44 of hexagonal or other non-circular shape to receive and conform to the peripheral shape of the nuts 41 whereby the nuts will be held against turning so as to permit of using a single tool on the bolt heads for tightening.

In the form of blade unit seen in Fig. 11 wherein four fusible elements 34 are used, two of said elements are located on each side of the plane of the blades and the two elements at one side are spaced apart by metallic collars 45 through which the bolts 40 extend. In this form the portions of the clips 36 which are parallel with the blades are necessarily spaced farther away from the blades to accommodate the fuse elements 105 and to receive the nuts 41.

The clips shown in Figs. 10 to 13 are not clamped by the bolts and nuts 40, 41, and therefore it is preferable to provide means for stabilizing the clips and preventing 110 rocking thereof on the blades. The means herein shown for that purpose comprises lugs 46 bent up from the clips along the edge of the blade-receiving slots 47 therein, said lugs extending along and engaging the faces 115 of the blades. If desired apertures 48 may be provided in the clips and blades to receive screws 49 so as to provide a more rigid fastening.

When it is necessary to renew or refill the fuse the end caps 27 are removed from the heads 21, 22, and the disk 30 is slipped off the end of its blade, whereupon the entire blade unit may be withdrawn from the casing through the left hand end thereof as viewed 125 in the drawings, it being necessary in beginning this removal to move the right hand blade transversely to the axis of the fuse so as to disengage the shoulders 38 from the abutment portions 28^a of the end wall 28 130

thereby permitting the blade to pass into and through the casing.

After the blade unit has been removed the bolts and nuts 40 and 41 are loosened somewhat, the unmelted ends of the blown fuse element or elements are removed, and a new fuse element is put in place to be clamped by the bolts. As shown in Fig. 15 the fuse element may have open end slots at its opposite ends, one slot extending parallel to the element and the other extending perpendicular thereto and opening onto one side edge. In inserting the element the end slot is first slipped around one of the bolts 41 and the side edge slot is then slipped around the other bolt after which the bolts are tightened and the blade unit is re-inserted into the casing from the left hand end. In doing this the bosses 25 on the disk 26 are positioned to engage in the recesses 24 in the head 21 when the blade unit is fully inserted into the casing, and the opposite blade will then be in position so that it may be moved sidewise or transverse to the axis of the fuse to engage its shoulders 38 with the abutments 28^a on the head 22. The disk 30 is then slipped over the blade until it abuts against the adjacent ledge 33, in which position the offset portion 31 of this disk will have its arcuate edge 31^a fitting snugly in the outer end of the head 22 and its chord-like portion 31^b fitting snugly about the ledge 33. When the said disk is in this position the blade will be held against movement transversely to the axis of the fuse or twisting or rotational movement about said axis, due to the interlocking and co-operating engagement of the head 22 and its end wall 28 with the disk 30 and the blade shoulders 38 and ledge 33 thereon. When the end cap 27 is screwed onto the head the disk 30 will be locked in operative position and any tendency for the blade to move longitudinally outward will be resisted by the disk through engagement therewith of the ledge 33. Furthermore longitudinal movement of the blade unit as a whole is prevented by the disk 26 which is clamped between the head 21 and its cap 27, also by the abutment of the shoulders 38 on its blade with the webs 23 on the head 21.

As is well understood, provision should be made in fuses of this character for the escape of gases generated upon blowing of a fuse. We have not attempted in the accompanying drawings to show the spaces or clearances between the parts which provide such gas-escape passages, but the construction is such that in the commercial manufacture of our fuses clearance is incidentally afforded for this purpose without special formation of construction of the parts. It is to be noted, however, that there is at no point any avenue for the gas to escape directly in a straight line from inside the casing to the atmosphere, but on the contrary the passages are

all indirect so that the gas will be baffled and thereby cooled and retarded and the danger of emitting fire or flame from the casing is thereby avoided.

In an extremely violent action of the fuse 70 when blowing it is possible that the insulating bar 37, which is usually made of fibre, may be burned or charred so that it is desirable at the time of renewing the fuse element to renew the bridge section also. With our construction such renewal of the bridge section 75 may be easily accomplished by completely removing the bolts 40 and associated parts of the means for clamping the fusible element to the blades, whereupon the bridge unit clips 80 36 may be slipped off of the inner ends of the blades and a whole new bridge section substituted. It will be understood that the number of fusible elements to be employed in any given fuse depends upon the desired 85 capacity of the fuse.

It will be seen that we have provided a renewable cartridge fuse which is of very strong and rugged construction and is adapted to fuses of very large capacity; also that 90 in renewing the fuse it is only necessary to remove two end caps and one disk to permit of withdrawing the entire blade unit from its casing. By providing a unitary terminal blade construction of this character the 95 operation of removing the ends of blown fuse elements and replacing new elements is facilitated and expedited.

We claim as our invention:

1. A refillable cartridge fuse having, in 100 combination, a casing comprising an insulating tube having metallic heads fixed to opposite ends thereof, a terminal blade unit comprising two blades spaced apart and secured together by an insulating bridge section and joined by a fusible element, a disk 105 permanently attached to one of said blades for closing one end of said casing, an annular cap threaded on one of said casing heads and surrounding the adjacent blade for 110 clamping said disk to said head, means for preventing relative rotation between said disk, and said head, the opposite head having an end wall closing approximately one-half of the casing and providing a pair of 115 opposed abutments against which shoulders on the adjacent blade are arranged to abut externally, a second disk slotted to slide upon the last mentioned blade and shaped to conform to the blade unit and head for holding 120 the blade in fixed position, and an annular cap threaded on the last mentioned head and surrounding said blade and arranged to clamp said second disk to its head, said terminal blade unit being withdrawable as a 125 whole from said casing by removing said end caps and said second disk.

2. A fuse comprising, in combination, a terminal blade having shoulders on opposite edges and an abutment adjacent said shoul-

ders, a metallic head having an end wall closing a portion of the opening through the head but leaving an aperture having an eccentric portion through which said blade may be passed through the head and a narrow portion central of the head adapted to receive said abutment and having portions at opposite ends of the narrow portion of said aperture against which said shoulders abut to prevent movement of said blade inwardly in the head, and means including a disk which closes the opening in the head cooperating with said abutment to prevent outward movement of said blade and also coacting with said head to hold said blade against movement transverse to the axis of the head or rotary movement about such axis.

3. A terminal blade unit for cartridge fuses comprising two blades, a fusible element joining said blades and a bridge section joining said blades and comprising metallic clips attached to the blades and joined by an insulating member, said clips being readily removable from said blades to permit substitution of a new bridge section.

4. A terminal blade unit for renewable cartridge fuses comprising, in combination, two blades, a fusible element joining said blades and a bridge section joining said blades, and comprising two metallic end clips joined by an insulating member, said end clips comprising portions lying parallel to the blades and perpendicular portions which are apertured to embrace adjacent ends of the blades whereby the clips are readily removable from the blades.

5. A terminal blade for renewable cartridge fuses comprising, in combination, two blades, a bridge section joining said blades and comprising two metallic clips joined by an insulating member each clip comprising a portion extending perpendicular to its blade and apertured to removably embrace the blade, and another portion extending parallel to its blade and having a nut-receiving aperture therein, a fusible element and means for fastening the ends of said fusible element to said blades comprising two bolts passing through said element and said blades and nuts on said bolts seated in said nut-receiving apertures in said clips.

6. A terminal blade unit for renewable cartridge fuses comprising, in combination, two blades, an insulating bridge section joining said blades, a fusible element, and two devices for fastening the ends of said fusible element to the respective blades, said bridge section being shaped to cooperate with said fastening devices to prevent rotation of a portion of said devices.

7. A terminal blade unit for renewable cartridge fuses comprising, in combination, two blades, a bridge section joining said blades and comprising a main insulating portion extending parallel to the blades and two metallic end portions having parts perpendicular to the blades and apertured to embrace the latter.

8. A terminal blade unit for renewable cartridge fuses comprising, in combination, two blades, an insulating bridge section joining said blades and comprising a main insulating portion extending parallel to the blades and two metallic end members having portions perpendicular to the blades and apertured to embrace the latter, a fusible element, and devices for securing said element to said blades, said bridge section cooperating with said devices to facilitate the manipulation of the latter.

9. A terminal blade unit for renewable cartridge fuses comprising, in combination, two blades, and an insulating bridge section joining said blades, said bridge section comprising metallic end portions having apertures therein through which the adjacent ends of said blades project.

10. A terminal blade unit for renewable cartridge fuses comprising, in combination, two blades, an insulating bridge section joining said blades comprising metallic ends having apertures therein through which the adjacent ends of said blades project, a fusible element, and removable devices for fastening said element to said blades, said blades being withdrawable from the apertures in said bridge section when said fastening devices and said fusible element are removed.

In testimony whereof we have hereunto affixed our signatures.

CLARENCE T. McDONALD.
HERBERT R. COOK.
